UNITED STATES PATENT OFFICE.

EDWARD O. KEATOR, OF DAYTON, OHIO.

CABLE CLIP AND CLAMP.

Application filed June 9, 1925. Serial No. 35,907.

This invention relates to an improvement in cable clips of the conventional type, such as is exemplified in the Crosby clip patented under Number 388,840 or in the improved 5 form of clip exemplified in any of the patented constructions of which that shown in Patent Number 1,511,972 is an example.

An object of this invention is to produce a new clip in which the scope of its usefulness has been enlarged and in which the efficiency of its functioning over that of the 10 clips of the same general type has been materially increased without adding to the operative mechanism of the clip or the number 15 of parts comprising the clip.

A further object is to produce an improved clip construction in which the improvement in the efficiency of the clip is such that it adapts it to other purposes than 20 those to which the usual clip could possibly be applied, and, in which, such purposes operate to render the clipping operation of secondary importance to the function to 25 which the clip is enabled to be applied by reason of the improved construction which I will now describe.

In the drawings Figure 1 is a perspective view showing my improved clip clamp construction used as a ground clamp such as is 20 employed in establishing a grounding connection for the circuits of radio or other electrical apparatus.

Figure 2 is a perspective view showing my improved clip clamp construction in use 25 as a device to secure an electric connection or tap from an electric cable or conduit by means of which a feed wire may conveniently be attached to such a conduit without resorting to solder or other troublesome 40 methods of attachment.

Figure 3 is a perspective view showing my improved clip clamp construction used for the same purpose as that shown in Fig. 2, but attached in a somewhat different 45 manner.

Figure 4 is a perspective view, upon a slightly enlarged scale, showing an improved form of clip embodying my invention, different from those forms shown in Figs. 50 1, 2 and 3.

Figure 5 is a sectional view showing to better advantage, the features of novelty embodied in the clip shown in Figure 4.

The improvement I will describe is applied to any type of cable clip in which a 55 base is employed with a U-shaped bolt to

clamp one or more sections between the branches of the U-bolt and the base by means of nuts on the threaded ends of the branches. I have chosen however, one of my 60 own patented clip constructions as an example for illustration of the application of the present invention to a typical cable clip. In this illustrated embodiment the enlarged views Figs. 4 and 5 show to best advantage a 65 clip consisting of a body 6 having a pair of wings 7 on one side and a pair of wings 8 on the other side of a cable receiving channel located between them. Between the wings of each pair are passed the branches 9 of the 70 U-shaped bolt 10 which carries the tightening nuts 11. The curve of the bolt also passes between the wings of each pair 7 and 8 and carries a cam 12 which has a cable engaging face. Thus far I have but described 75 a well known clip and will now show its application to my invention. Formed as an extension of the clip body is a pin 13 which is supported by side arms 14 and 15 projecting from the clip body. This pin 13 constitutes the single item upon which the gist 80 of my invention depends, and in the drawing I have shown several applications of this idea to different purposes.

In Figures 1, 2 and 3 I have shown a construction in which the body pin 13 is incorporated with a clip body having sleeve extensions 16 and 17 through which the threaded branches 18 and 19 of an enlarged 85 U-shaped bolt 20 extend. These branches 90 carry nuts 21 and 22. In the form shown in Figure 1 the U-bolt 10 of the clip is provided with a cam 12, but in Figs. 2 and 3 the cam is omitted and nothing but the U-bolt 10 is provided to perform the clamping operation as in the older style of clip. Also, in the form shown in Figure 1 the ends of the branches of the large U-bolts are sharpened at points 23 and 24 while in the usage 95 shown in Figures 2 and 3 they are blunt. 100

In Figure 1 the particular application of the invention is for the purpose of forming an electrically efficient ground connection for any electrical installation, as for example a radio receiver, in which capacity 105 it operates as a ground clamp. In such a usage the grounding wire 25 to which the clamp is attached, preferably is connected with a conveniently located water or other pipe 26 which is considered the best medium 110 through which a desirable ground connection may be established. In establishing

such a connection by means of the ground clamp I have shown in Figure 1, I first place the clamp in the position it is to occupy and then drive the points 23 and 24 into the metal of the pipe. The surface of the pipe between the two depressions so made, is then cleaned and the ground wire 25 is wrapped around the pipe as shown. The clamp is then brought into position with the main portion as well as the end of the wire lying in the channel between the side arms 14 and 15 and the pairs of wings forming the sides of the channel. The end of the wire is then passed back of and around the body pin 13, being brought back again into the channel between the wings, where, with the main portion of the wire it is clamped tightly by the cam being tightened upon the three bights thus lying in the channel. Nuts 21 and 22 are then turned to tighten the clamped wire by moving the sleeves 16 and 17 of the clip body away from the pipe, thus causing the clip to pull upon and to tighten the wrappings of the wire upon the pipe and at the same time tighten the entire clamp against displacement. Electrical contact is assured because of the points 23 and 24 biting into the metal of the pipe and also the many points of intimate contact of the wire with the pipe as well as with the clip elements. And now, to show the advantage attained by the looping or snubbing of the wire around the body pin of the clip, followed by a simultaneous clipping of the snubbed end with the main portion of the wire and that portion of the end which was just laid in the channel. If a strain be placed upon the pipe, the clamp or the wire, there will result a placing of a tension upon the looped or snubbed end of the wire which will tighten it over the body pin and thus operate to tighten not only the clip elements, but also the wire upon itself as it were and operate to resist any further slipping tendency so that automatic tightening is provided up to the tensile strength of the wire itself.

In Fig. 2 I show an application of my improved clamp to use for establishing an electrical tap or connection from an electric conduit or cable 27. To establish such a connection the U-bolt 20 is wrapped upon the curved or bent portion thereof with a sufficient number of turns 28 of the feed wire 29 to contact the cable 27 throughout the complete distance of the contact of the bolt with the cable. The clip body 6 is now placed upon the bolt branches 18 and 19 in a reverse position to that shown in Figure 1, that is, with the side arms 14 and 15 holding the body pin 13 toward the cable instead of away from it as in Figure 1. The feed wire and its end 30 are then brought into the clip cable receiving channel, the end 30 preferably being brought over the body pin

as shown. The clip U-bolt 10 is then brought into position over the end 30 and the wire 29 itself and is clamped tightly thereon. It will be seen upon reference to the drawing that the cam 12 as shown in Figure 1 has been omitted in Figure 2. This is but for purposes of showing how the usual clipping means may be employed in my improved construction. With both bights of the feed wire thus clipped tightly, the nuts 21 and 22 are turned to push the clip body toward the cable 27, thereby pressing the side arms 14 and 15, the body pin 13 and the end 30 of the feed wire into quite intimate contact with the cable while at the same time drawing the windings 28 into equally intimate contact with the cable on its opposite surface. This clipping and clamping action is so free from slippage and is made increasingly more and more so as tension is brought to bear by the tightening of nuts 21 and 22, that it may be carried to the strength of the screw threads of the branches 18 and 19 of the U-bolt 20 and of the nuts 21 and 22.

In Figure 3, the identical clamp as shown in Figure 2, is shown. However, I have shown a different manner of fastening it to the cable 27. In this attachment the feed wire 32, instead of being wrapped around the curved portion of the clamp U-bolt as shown at 28 in Figure 2, is given a few turns about the clip body pin as shown at 31. The wire itself as well as its end 33 are brought into the clip cable channel and the clip U-bolt 10 is tightened upon them. Then placing the clip upon the branches of the clamp U-bolt with the turns 31 against the cable, the nuts 21 and 22 are tightened to press the turns of the feed wire tightly against the strands of the feed cable as shown. Thus intimate contact and consequent electrical connection is established between the cable strands and the feed wire.

In Figure 4 I have shown my improved clip construction in which the side arms 14 and 15 of the body not only carry the body pin 13 but also further extensions 34 and 35 in which a removable bolt 36 may be mounted, or between which a unitary pin 37, see Figure 5, is formed. This idea may be carried further in the formation of hooks or other special forms of means for attaching the improved clip to clevises, poles or other rigging as suggested in Fig. 5.

Having thus described my improved clip I may again bring out the two features which either singly or in conjunction with each other, cooperate with a clip of the usual type or of my own patented constructions, to which reference has been made, in producing a construction which places cable clips in entirely new fields of usefulness and with increased efficiency of functioning of the clip itself. I refer particularly to the

body pin 13 and the additional feature of the clamp U-bolt within the body sleeves 16 and 17. I may also point out that in the clip clamp construction I have disclosed I 5 have produced a structure in which a cable clip has been provided with two completely independent U-bolts, each functioning independently of the other and each performing an entirely different purpose in the operation 10 of the structure as a whole, but in which both purposes are distinctly cooperative with the other to enable the entire clip clamp to function as a unit. Such an improved clip clamp construction is set forth in the following 15 appended claims:

1. A cable clip comprising a body having a cable receiving channel therein, a bolt lug on the body to each side of the channel, a U bolt passing over and across said channel 20 and through the lugs and having tightening means on its ends, side arms extending from the body, and a pin extending between and rigid with the arms, adapted to receive the cable from the channel in looped frictional 25 condition around it.

2. A cable clip and clamp comprising a U-shaped bolt, a body reciprocally mounted on the branches of the bolt, nuts adjustably mounted on the branches, adapted to bring 30 the body into gripping engagement with cables located between the branches, a second U-shaped bolt mounted for reciprocation of its branches in the body at an angle to those of the first mentioned U-shaped 35 bolt, and nuts adjustably mounted on the branches of the second mentioned bolt, adapted to create relative movement of the clip unit comprising the body, the first mentioned bolt, and the cables gripped by the 40 body and the first mentioned bolt, toward and away from the base of the second mentioned U-bolt.

3. A cable clip and clamp comprising a U-shaped bolt, a body slidable thereon, 45 clamping nuts for the ends of the bolt, adapted to move the body into clamping engagement with the bights of a looped cable located between the branches of the bolt, side

arms extending from the body in the direction of the cable gripped by the U-bolt, 50 a pin at the ends of the arms and extending between them to receive the loop of the cable, and a second U-shaped bolt mounted for reciprocation of its branches in the body at an angle to those of the first mentioned 55 U-shaped bolt, and means adjustably mounted on the branches of the second mentioned bolt, adapted to create relative movement of the clip unit comprising the body, side arms, pin, first mentioned bolt and looped cable 60 gripped thereby, toward or away from the base of the second mentioned U-bolt.

4. A cable clip and clamp comprising a cable clip of conventional design, and a second U-bolt mounted in the body of the clip 65 for reciprocation therein in a plane at an angle to the body of the clip, a pin being located on the body and lying in the plane of the second U-bolt, whereby the cable which is gripped by the clip may be looped 70 about the pin to snub it against slippage in the clip when the second mentioned U-bolt when positioned relatively to an abutment is caused to move the clip in cable tightening direction. 75

5. A cable clip and clamp comprising a cable clip of conventional form, and a second U-bolt mounted in the body of the clip for reciprocation therein in a plane at an angle to the body of the clip, a pin being 80 located on the body, in extended relation thereto, and lying in a plane substantially parallel with the second U-bolt, the second U-bolt being adapted to embrace an object to which the clip is to be clamped, the pin 85 receiving a loop of the cable which is gripped by the clip, whereby the cable is snubbed against slippage in the clip, and means on the second mentioned U-bolt adapted to move the clip toward the object 90 to which it is to be clamped, whereby the cable loop over the pin will be clamped tightly against the object.

In testimony whereof I have hereunto affixed my signature.

EDWARD O. KEATOR.
